UNITED STATES PATENT OFFICE.

ELBRIDGE G. KELLEY, OF PEABODY, MASSACHUSETTS.

DESIGN FOR A PULLEY-BLOCK.

SPECIFICATION forming part of Design No. 34,324, dated April 2, 1901.

Application filed March 5, 1901. Serial No. 49,969. Term of patent 3½ years.

To all whom it may concern:

Be it known that I, ELBRIDGE G. KELLEY, a citizen of the United States, residing at Peabody, in the county of Essex and State of Massachusetts, have invented and produced a new and original Design for Pulley-Blocks; and I do hereby declare the following to be a full, clear, and exact description of the same, reference being had to the accompanying drawings, forming a part thereof.

Figure 1 represents a side elevation of a pulley-block, showing my new design; and Fig. 2 represents a sectional view taken on the line 2 2 of Fig. 1.

The leading or material feature of my design consists in the shape of the side pieces of a pulley-block, as shown in the drawings. The contour of such side piece A is leaf or

spoon shaped, terminating at the bottom as a rounded projection B, having concave sides C C, as shown in Fig. 1. The middle portion D of such side piece is convex and made slightly concave near the outer edge A, as shown at E in the drawings

Having described my invention, what I claim as new, and desire to secure by Letters Patent, is—

The design for a pulley-block as herein shown and described.

In testimony whereof I have affixed my signature in presence of two witnesses.

ELBRIDGE G. KELLEY.
